UNITED STATES PATENT OFFICE.

FRANK GUY, OF SPRINGFIELD, ILLINOIS.

MINER'S CARBID-LAMP.

1,097,716.

Specification of Letters Patent.

Patented May 26, 1914.

Application filed March 1, 1911. Serial No. 611,706.

To all whom it may concern:

Be it known that I, FRANK GUY, a citizen of the United States, residing at Springfield, in the county of Sangamon and State of Illinois, have invented certain new and useful Improvements in Miners' Carbid-Lamps, of which the following is a specification.

This invention relates to the subject of portable lamps, more particularly of the 10 type containing their own gas-generating means.

To this end the invention contemplates a simple and practical portable lamp so designed and constructed as to be especially 15 useful as a miner's lamp, and embodying means which provide for the safe, reliable and economical generation of acetylene gas, the production of which is under the immediate and complete control of the operator.

20 Other objects of the invention include the provision of means for thoroughly filtering and cooling the generated gas before its delivery to the lamp burner, besides insuring the maintenance of the light during blasting operations. In the latter connection the invention provides novel means to compensate for the sudden increase in external pressure, and gusts of wind, resulting from the concussion when blasting shots are fired, and 25 30 which very frequently blow out the light of the miner's lamp. This is avoided in the present invention and, furthermore, the compensating devices also serve to prevent blowing water out of the reservoir upon an increase in the internal gas pressure in the 35 main gas chamber of the casing.

Another object of the invention is to provide a novel water-supply device that is so constructed and valved as to insure a reliable feed of the water into the carbid, while at the same time being protected against clogging.

40 A general object of the invention is to provide a lamp of the character described that is exceedingly simple, and not easily broken or deranged.

The invention consists in the novel construction, combination and arrangement of parts hereinafter more fully described, illustrated and claimed.

A preferred embodiment of the invention is shown in the accompanying drawings, in which—

55 Figure 1 is a side elevation of an acetylene lamp embodying the present invention. Fig. 2 is a vertical longitudinal sectional

view thereof. Fig. 3 is a detail sectional view through the pressure compensating device and the body of the lamp on the line 3—3 of Fig. 1. Fig. 4 is a detail sectional view showing the guard screen attachment for the burner. 60

Like references designate corresponding parts in the several figures of the drawing.

The improved lamp embodies a casing of 65 any suitable design and capacity, but preferably of a general cylindrical form, and also preferably made of sheet metal. This casing is designated in its entirety by the reference numeral 1. A hook 2 on the casing 1 serves 70 to support the lamp on the user's cap and also serves as the handle of the lamp.

The casing 1 has suitably fitted therein an interior separating diaphragm 3. This diaphragm divides the interior of the casing 75 into an upper water reservoir 4, and a lower main gas and carbid chamber 5. The separating diaphragm 3 is preferably downwardly dished and forms the bottom of the water reservoir 4, while the top 6 of the 80 casing 1 constitutes the top of said reservoir and is provided with a filling opening 7 for water, the said filling opening being closed by means of a removable filler cap 8. The cap 8 is of hollow formation and is provided 85 at top and bottom with vent orifices 9, which are in communication with the interior of the cap and with the reservoir 4, thus providing what may be termed a water trap, within the cap, to prevent the water blowing 90 out of the reservoir upon an increase in the gas pressure in the main gas chamber 5.

The main gas chamber 5 is provided with an open bottom adapted to be closed by a removable bottom cap 10, preferably in the 95 form of a screw-cap engaging threads 11 on the lower end portion of the casing, as plainly appears from the drawings.

Water is supplied to the chemical in the chamber 5 by a water-supply device consisting of a tube 12 arranged longitudinally of the casing, and having its upper end projecting through the casing top 6, while its lower end lies within the gas chamber 5 and is provided with the bottom outlet opening 13, 100 which is covered and uncovered, more or less, by a valve head or button 14, carried at the lower extremity of an adjustable valve stem 15 extending longitudinally through the tube 12 and provided at its upper end 110 with an exterior operating handle 16. Also the upper end portion of the stem 15 is rigid

with an adjusting member 17 consisting of a hollow screw engaging a threaded socket 18 at the upper end of the bore through the tube. The tube 12 has inlet apertures 19 in communication with its bore and with the water reservoir 4. A feature of practical importance in the present invention resides in the self-cleaning action of the valve head or button 14. By reason of the threaded member 17, at the upper end of the valve stem 15, it will be observed that in the opening and closing operation, the valve head or button 14 not only has a movement toward and from the valve seat at the outlet end of the tube 12, but also has a rotary movement with the result that in turning the said valve head or button will dislodge carbid crust or dust on and about the lower end of the valve tube, thereby keeping the outlet for the tube at all times perfectly clear. In other words the valve head or button has a revolving or grinding action at the lower end of the valve tube which insures the maintenance of the water supply for the carbid chamber. Below the separating diaphragm 3 the casing has fitted therein a filtering diaphragm consisting of a transverse filter screen 20 a porous absorbent sheet 21, such as blotting paper at the under side of the screen 20, and a filter packing of loose material 22, filling the space between said screen 20 and the diaphragm 3, and which space constitutes a filtered gas chamber. This latter chamber is in communication with the gas outlet neck 23 for the external gas burner 24 fitted therein, and is also in communication with a gas port 31 in communication with an externally arranged expandible and contractible pressure-compensating device 26, which device preferably consists of a closed rubber bulb.

The tube 12 extends downwardly into the carbid box in such a position that the lower part of the tube, and the valve 14, will be surrounded by the mass of carbid in the box. The end of the tube is flat and the circular valve 14, of the same outer diameter as the tube, seats on the entire area of the lower end of the tube, and when the valve is rotated and moved upwardly it will crush the accretion of ash, &c., on the entire area of the end of the tube, and when the valve is lowered to the necessary extent water from the tube will be diffused radially between the top of the valve and the end of the tube and will be applied in the mass of carbid all around the tube. This mode of diffusion is new and admits of applying the water most effectively on a relatively large area of the carbid.

In practice it is found that the concussions of shot firing tend to suddenly detach the flame from the burner tip and thus extinguish the flame, but that this detaching and extinguishing of the flame may be avoided

if the gas pressure at the burner tip be increased coincidently with the concussion and to a degree corresponding to the force of the concussion; but it is also found that if the pressure of gas at the burner tip be too suddenly increased the sudden excessive pressure will blow the flame away from the small orifice of the burner tip and thus extinguish the light. I therefore provide means responsive to the concussion and effective to increase the gas pressure at the burner tip at the instant concussion and likewise effective to temper the pressure at the burner tip. This means and the mode of its operation will now be described.

Referring to Figs. 2 and 3, it will be seen that the burner tip 24 and the compressible bulb 26 are both in communication with the chamber formed by the conjunction of the diaphragm 3, the filter screen 20, and the circular wall of the casing 1, and that said chamber is filled with loose or interstitial material, the interstices of which are filled with gas. In case of concussion, the volume of gas contained in the bulb 26 will be forced inward through the interstitial material which will act as a cushion to absorb and distribute the concussive force to an extent sufficient to prevent such sudden and excessive increase of pressure at the burner tip as would be likely to extinguish the flame and never-the-less produce such timely and proper increase of pressure at the burner tip as will prevent the extinguishing of the flame by the force of the concussion.

When the lamp is used in the mine, a reflector 27 may be fitted over the gas outlet 23, and another practical use is suggested in Fig. 4, which illustrates a cylindrical closed guard screen 28 fitted at one closed end over the outlet 23 and having the burner 24 disposed therein and protected thereby from inflammable material, such as hay and the like, while the lamp is in use in the stable or in the mine. The closed end of the guard-screen is rigidly connected with a collar 29 surrounding the burner tube 23. A screw 30 connects the collar with the burner tube. When the collar and the connected guard-screen are in place on the burner tube, the axis of the guard-screen is parallel to and above the outwardly extended axis of the burner such a distance that the flame which is naturally projected outwardly and upwardly from the burner tip, will not penetrate the wall of the guard screen, and therefore cannot ignite inflammable material adjacent to the screen.

The functions of the water-supply device and the filtering diaphragm will be readily understood from the foregoing description, but in explanation of the action of the pressure-compensating device 26 it should be stated that the concussion resulting from the firing of blasting shots creates an external

pressure on the bulb or bag 26, which in turn forces the gas with increased pressure through the burner with a result of tending to prevent the flame from being blown out.

- 5 Other objects and advantages will be apparent without further description, and it will also be understood that changes in the form, proportion and minor details of construction may be resorted to without departing from the spirit or sacrificing any of the advantages of the invention.

What I claim is:—

1. In an acetylene lamp, in combination with a lamp-body comprising a water chamber and a carbid chamber; a stationary tube in communication with the water chamber and having one terminal within the carbid chamber; a valve-stem adapted to rotate and move longitudinally within said tube; 20 and a valve rigid on the valve stem and having a face adapted to engage and grind on the terminal of the tube within the carbid chamber.
2. In an acetylene lamp, the combination of a carbid box; a tube extending into the box in such position that the terminal part of the tube will be surrounded by the mass of carbid in the box; means for supplying water in the tube; and a valve seating on one 30 end of the tube and effective to diffuse water radially into the mass of carbid surrounding the terminal part of the tube.
3. In an acetylene lamp, the combination of a carbid box; a tube extending into the carbid box in such position that the terminal part of the tube will be surrounded by the mass of carbid in the box; means for supplying water in the tube; and a rotative and vertically movable valve adapted to 40 seat on one end of the tube and effective to crush and grind the accretion on the end of the tube and likewise effective to diffuse water radially into the mass of carbid surrounding the tube.
4. Valve mechanism for acetylene lamps; comprising a tube of suitable diameter positioned to be partially immersed in the charge of carbid in the lamp; a valve of substantially the same diameter as the tube 50 and adapted to seat on the immersed end of the tube; and means for rotating the valve to crush accretion on the immersed end of the tube, and moving the valve in the longitudinal direction of the tube to control 55 radial diffusion of liquid from the tube into

the charge of carbid surrounding the valve and the immersed part of the tube.

5. Valve mechanism for acetylene lamps; comprising a tube having a flat end adapted to serve as a seat for a rotative valve, a valve 60 of substantially the same diameter as the tube and fitted to seat on the entire area of the flat end of the tube; and means for rotating the valve and moving it in the longitudinal direction of the tube, to control radial diffusion of liquid between the valve 65 and the valve seat.

6. In an acetylene lamp, the combination of a receptacle adapted to contain a quantity of carbid; a water-supply device having a terminal valve-seat in position to be surrounded by the body of carbid in the receptacle; a valve adapted to seat on said terminal valve-seat; and means for moving the valve relative to the terminal valve-seat 75 to control radial diffusion of water between the valve and the valve-seat into the body of carbid surrounding them.

7. In an acetylene lamp, the combination of a receptacle adapted to contain a quantity of carbid; a water-supply device having a terminal valve-seat in position to be surrounded by the body of carbid in the receptacle; a valve adapted to seat on said terminal valve-seat, and means for moving the valve toward or away from the valve-seat and rotating the valve relative to the valve-seat, to control the radial diffusion of water into the body of carbid surrounding them and to crush accretion on the valve and the 90 valve-seat.

8. In an acetylene lamp, in combination with a lamp body comprising a water chamber and a carbid chamber; a stationary tube in communication with the water chamber 95 and having one terminal within the carbid chamber, also having a screw-threaded part; a valve stem within said tube; means for rotating the valve stem; a screw rigid on the valve stem and engaging in the screw-threaded part of the tube, and a valve rigid on the valve stem and having a face adapted to grind and seat on the terminal of the tube within the carbid chamber.

In testimony whereof I hereunto affix my 105 signature in the presence of two witnesses.

FRANK GUY.
